AUTOMATIC PROPELLER BLADE SUPPORT

Glen T. Lampton, West Hartford, Conn., assignor
to United Aircraft Corporation, Hartford,
Conn., a corporation of Delaware

Application March 3, 1945, Serial No. 580,835

3 Claims. (Cl. 170—160.52)

1

This invention relates to a flexible propeller blade support particularly for use in an aircraft propeller of the type shown and claimed in an application of Glen T. Lampton and Donald W. Perin, Serial No. 580,834, filed concurrently herewith, that has the pitch angle of its blades automatically reduced as its thrust increases, so that the propeller, within limits, will be self-regulating to maintain constant engine speed.

A primary object of this invention is a blade support which will provide the necessary flexibility in a simple structure.

Another object of the invention is a blade support comprising a central bundle of wires extending centrally and diametrically through the driving hub and axially within the blades.

A further object is the provision of bell-mouthed, cable supporting ferrules within the hub and blades so that each blade may hinge about a point intermediate its length.

Other objects and advantages will be apparent from the specification and claims and from the drawing which illustrates what is now considered to be a preferred embodiment of the invention.

In the drawings,

Fig. 1 is a longitudinal sectional view through the principal parts of a propeller made in accordance with the present invention and,

Fig. 2 is a similar view, partly in section, taken on a plane at right angles to the plane of Fig. 1.

Referring more in detail to the figures of the drawing, there is shown a two-bladed propeller made in accordance with the present invention.

The blades 10 shown in the drawing are of conventional wooden construction and have an elongated ferrule 12 extending axially therein from their hub ends for a portion of their length, the inner end of the opening extending through the ferrule being bell-mouthed. Preferably, and as shown in the drawing, the ferrule 12 is threadedly connected to its blade, the threads being so formed that they will have maximum gripping power within the material of which the blade is formed.

The driving hub 14 for the blades 10 is provided with an elongated sleeve 16 extending therethrough which in the two-bladed form of propeller shown in the drawing, may extend diametrically through the center of rotation of the

hub. The opposite ends of the opening extending through the sleeve 16 are bell-mouthed similarly to the ferrules 12. Extending through this sleeve 16 in the hub 14 and into the ferrules 12 secured within the blades 10 is a central bundle of wire strands 18, these wires preferably being formed into a spirally wound cable. The outer ends of the cable or strands of wire 18 preferably may be secured within the ferrules 12 by soldering, tinning, brazing, or otherwise securing the cable to the portion of the ferrule within which the opening is of uniform diameter, that is, beyond the bell-mouth portion. For a purpose presently to be referred to, the cable may be wound 15 with a helix of the opposite hand to the rotation of the blade; that is, for a propeller having a right hand rotation, the cable 18 would have a left hand helix.

The sleeve 16 is secured to the hub by clamping it thereto by means of a number of bolts 20, in addition, there may be a transverse shear pin 22 provided extending through the hub 14 and sleeve 16 by means of which the sleeve is locked in position. As shown in Fig. 2, the hub 14 is 25 split and its opposite side portions are drawn together into frictional contact with the outer surface of the sleeve 16.

The shear pin 22 is installed after horizontal balance of the propeller is obtained by shifting 30 the entire blade assembly. It is apparent that if one blade is thrown from the propeller due to failure of the threads in the blade or by fatigue failure of the cable 18, the unbalanced centrifugal load will shear the pin 22 and pull the remainder 35 of the blade assembly through the hub 14 so that both blades 10 will leave the hub substantially simultaneously. This will instantly remove the unbalanced condition before serious damage can be done to the engine or its mountings and leave 40 the plane in condition so that the pilot may make a normal deadstick landing.

The centrifugal forces acting on the blades 10 serve to stretch and thus tend to slightly unwind the cable 18. Normally there is a pitch reducing 45 moment in the propeller blades 10 due to centrifugal forces which, in the present instance, is balanced out by forces in shear acting within the wire cable 18 and by the reaction on the ball seat presently to be referred to. By using a left hand cable 18 for a right hand rotation propeller,

3

this reaction is used to advantage to reduce the load on the point of attachment of the blade at the inner end of the post for the reason that the unwinding of the cable tends to increase the propeller blade pitch.

By reason of the cable 18 extending through the sleeve 16 in the hub 14 and through the ferrule 12 and the outer ends of the opening within the sleeve 16 being bell-mouthing and the inner ends of the ferrule 12 also being bell-mouthing, the blades 10 may flex within limited angles relative to their driving hub 14 in any direction. The cable 18, made up of numerous strands and located centrally and longitudinally of the blades, permits this angular adjustment of the blades with but slight torsional resistance. Also the bell-mouthing of the sleeve 16 and the ferrules 12 permits flexing of the cable 18 over a material length so that stresses of the cable strands due to this flexing are kept relatively low.

To retain the blades 10 in their positions relative to the hub 14, while permitting limited angular movement in the plane of rotation and in the direction of flight, the skirts of the blades 10 have collars 24 surrounding them preferably of resilient material such as rubber to suppress vibrations. Surrounding each of the resilient collars 24 is a two-part clamping member 26 having an inward radially extending post 28 adjacent the trailing edge of the blade 10. This post 28 at its outer end engages within a portion of the clamp formed by members 26 and at its inner end engages within an opening in a resilient sleeve housed within a portion of the hub. The blades mounted in this manner may deflect or tilt in the direction of flight causing the skirt of the blade to move slightly downstream.

The pivotal or hinge point at which the blade deflects or tilts is at or near the joint formed by the bell-mouth ends of the openings in the sleeve and ferrule. This point is at an intermediate portion of the blade and at a substantial radial distance from its center of rotation. This flexing movement of the blades 10 takes place while the trailing edge of the blade is held against movement by the substantially fixed position of the inner end of the post 28. This movement, therefore, results in the pitch of the blade being changed. The greater the deflection of the blade due to thrust of the blade, the more the pitch of the blade is changed.

As the cable 18 is wound with a left hand helix and the blade 10 has a right hand rotation, the centrifugal forces acting on the blade tend to unwind the cable slightly, this reduces the pressure acting on the post 28 forming the fixed point of attachment of the blade to the hub 14.

For a given propeller design the upstream deflection of the blade may be computed with a reasonable degree of precision and thereafter the location of the point of attachment of the heel of the blade to the hub can be determined so that the change in pitch under differences in thrust is of such an amount that substantially constant engine speed can be maintained throughout the entire velocity range of the airplane at one throttle setting.

If the airplane exceeds its designed velocity as during a dive the propeller will automatically increase its pitch beyond its normal level flight value and will maintain constant propeller speed under this regime.

At reasonably constant values of V/nD , (where V equals velocity of the plane, n equals R. P. M. and D equals diameter of propeller) which exist during part throttle level flight of an aircraft,

4

the thrust torque and centrifugal loads will vary as the square of the engine speed. Since these forces are designed to be in equilibrium, it follows that the propeller will only change pitch in response to a change in altitude, and consequent change in forward velocity of the aircraft, and that the pitch will be independent of throttle position in level flight. The propeller, therefore, behaves substantially as a fixed pitch propeller under engine throttle changes in level flight.

If so desired, the design features can be predetermined and the point of attachment of the heel of the blade to the hub positioned so that propeller engine combination, instead of maintaining constant speed under all conditions of flight at a single throttle setting, will provide a high speed for take-off and a lower speed in level flight. With the propeller so adjusted and the throttle maintained at full throttle position the propeller speed will slow down as the airplane gathers forward velocity during and after take-off thus providing a propeller which will automatically give the increased power desired for take-off.

For further explanation of the operation of the propeller forming the subject matter of this application reference may be had to the companion application 580,834 in which the present applicant is one of the joint inventors.

It is to be understood that the invention is not limited to the specific embodiment herein illustrated and described, but may be used in other ways without departure from the spirit of the invention as defined by the following claims:

I claim:

1. A self regulating propeller comprising in combination, a central driving hub, aligned blades extending radially in opposite directions from said hub, and blade mounting means pivotally connecting said blades with said hub for movement about axes extending longitudinally and transversely of said blade, said mounting means comprising, an elongated sleeve secured in and extending diametrically through said hub, the ends of the opening extending through said sleeve being bell-mouthed, ferrules aligned with said sleeve and extending centrally and longitudinally into said blades from their hub ends and secured therein, said ferrules at their hub ends being bell-mouthed, and a flexible cable, said cable extending longitudinally through and secured to said sleeve and having its ends extending into and secured to said ferrules beyond their bell-mouthed ends, said sleeve extending substantially the entire distance between said ferrules and terminating adjacent the bell-mouthed ends of said ferrules, and supporting said cable except adjacent said bell-mouthed ends whereby, said unsupported portion of said flexible cable provides transverse and longitudinal, pivotal, support for said blades and the support portion of said cable restrains transverse and longitudinal movement of adjacent portions of said sleeve and ferrules.

2. The propeller blade mounting means claimed in claim 1 in which the flexible cable is a multi-strand helically wound cable.

3. In a self regulating propeller having a driving hub, and a plurality of blades, means for flexibly mounting said blades in the hub for limited movement in any transverse direction with respect to said hub, a central multi-strand flexible cable retaining said blades against radial outward movement and providing a pivotal support therefor, aligned ferrules secured within said

blades and to which the opposite ends of said cable are attached, said ferrules having inwardly directed bell-mouths, and a sleeve extending diametrically through and secured to said hub and through which said cable extends, said sleeve extending into said blades substantially the entire distance between said ferrules and terminating adjacent the bell-mouthed portions of said ferrules to provide transverse support for, and a transversely flexible mounting for, said 10 blades with respect to the hub.
